UNITED STATES PATENT OFFICE.

MICHAEL WOODS, OF CARLTON, AND THOMAS JEFFERSON GILBERT, OF BRUNSWICK,
VICTORIA, AUSTRALIA.

RAIL MILLING AND DRESSING MACHINE.

No. 918,634.

Specification of Letters Patent. Patented April 20, 1909.

Application filed May 20, 1907. Serial No. 374,711.

To all whom it may concern:

Be it known that we, MICHAEL WOODS and THOMAS JEFFERSON GILBERT, subjects of the King of Great Britain and Ireland, residing 5 at 309 Pidgon street, Princess Hill, Carlton, and of 1 Minnie street, Brunswick, respectively, both in the county of Bourke, State of Victoria, Commonwealth of Australia, have invented a certain new and useful Improved 10 Rail Milling and Dressing Machine, of which the following is a specification.

Our invention relates to improvements in portable milling and dressing machines, for plain or grooved rails, which are adapted to 15 reshape the said rails to conform to a suitable model rail, without removal from their position in the track, *i. e. in situ*.

The heads of both plain and grooved rails, even on installation, are often uneven at the 20 joints and in a short time the original unevenness becomes accentuated by the formation of additional undulations. Moreover the heads of the plain or ordinary rail, especially on the sharp curves, are gouged by the 25 wheel-flanges, to such an extent that lips or ridges are formed immediately below the line of contact of the head with the wheel-flange and with the result that derailment is frequent. Similar ridges form in the grooves 30 of street railway rails and, in addition, the wearing down of the heads renders the grooves shallow, with the result that their function is gradually destroyed.

Our machines consist essentially of a man- 35 ual- or power-propelled milling and dressing mechanism adapted to travel upon three or four wheels, as may be required, and capable of being conveniently transferred from one track to another. Suitable vertical and 40 lateral adjusting means are provided, which permit of the complete reversal of the machine and of adjusting the height of the rear end of the machine, as well as the lateral movement of the machine-platform and the cutting tool.

Referring to the drawings which form a part of this specification: Figure 1 is a plan of our invention as applied to grooved rails. Parts have been removed for convenience of 50 illustration. Fig. 1^a is a front elevation of the forked lever and its parts for longitudinally moving the grinding wheel-spindle. Fig. 2 is a side elevation of Fig. 1. Parts

have been removed for convenience of illustration. The figure includes parts not shown 55 in Fig. 1, such as the bracket and hand wheel operating the rollers which are only used on plain headed rails. It is shown merely to indicate its relative position. Fig. 3 is an end elevation on an enlarged scale and partly 60 in section of the vertical feeding wheel and the model rail wheel and shows a model rail in position and its relation to a plain headed rail. The means employed for retaining and adjusting the model rail are shown. Fig. 4 65 is a side elevation of a model rail and the chairs or supports in which it rests. The vertical feeding wheel is shown. Fig. 5 is a plan of a model rail in place. Portions are broken away for convenience of illustration. 70 Fig. 6 is a side elevation of a worn or deformed rail and beyond it a model rail depressed in the center. The clamps which secure the model rail to the deformed one are removed. Fig. 7 is an elevation partly in 75 section of the axle near the cutting tool. The gear whereby the machine is propelled and the means of conveying a lateral movement to the front of the platform are seen. Fig. 8 is an elevation partly in section on an 80 enlarged scale of the mechanism used for lifting the machine so that it may be turned end for end. Fig. 9 is an elevation partly in section of a double flanged wheel. Fig. 10 is an elevation partly in section of a platform 85 attachment for laterally adjusting the plat- form when plain rails are being reformed.

Similar letters of reference indicate similar or corresponding parts where they occur in the several views.

Our invention includes a platform A. This, when reforming rails, is supported (Figs. 1 and 2) upon two single flanged traveling wheels B and an unflanged or plain wheel X³ 95 having a transversely rectilinear periphery (Fig. 1). When propelling the machine over substantial distances, a fourth single flanged laterally moved wheel C rests upon the rail and the said unflanged wheel X³ is replaced by an ordinary single flanged wheel. The 100 said wheel C turns on an axle D supported on the outer end of an arm E, provided with two collars F⁴, capable of longitudinal movement upon the axle. The respective positions of the wheels during the dressing operation are illustrated in Fig. 1.

Two wheels F, mounted on longitudinal axles, are disposed at the front end of the machine and at the rear end is a similarly mounted wheel F, capable of vertical movement, upon the operation of a hand wheel G. The front wheels F are elevated or depressed by worm wheels H, arranged to engage a worm H⁵, mounted on a shaft H⁶ and adapted to be rotated by a handle H⁷. One of the front wheels F, is provided with a toothed ring J, which is revolved by a pinion K, when the handle L is rotated. The shaft upon which said pinion is mounted, may be extended and provided with a second pinion 10 capable of engaging a toothed ring provided on the rear wheel F.

To move the machine from track to track, cross-over rails are placed underneath the wheels F and over the tracks. The hand wheel G and the handle H⁷ are then rotated, forcing the wheels F downwardly upon the cross-over rails and lifting the platform A upwardly. The rear traveling wheel B, can be elevated or depressed in relation to the frame by a hand wheel B. Said wheel B has (see Fig. 9) an internal flange and an external flange W³, being thereby applicable to both railway and street railway rails. The external flange W³ is removed when street rail-way rails are being treated or when the machine is being propelled distances over railroad rails. Near the rear end of the machine, and underneath it, is (Figs. 1, 2 and 3) a vertical feed wheel M mounted upon one end of an axle N (Figs. 2 and 4). Above said axle is a vertically movable stem O, adapted to elevate or depress the rear of the platform A, when the hand-wheel P is rotated as herein-after described.

The machine can be rapidly propelled backward and forward by any form of motor as follows:—On the end of the first motion or motor shaft R is positioned (Figs. 1 and 2) a worm S, which drives a worm wheel T and rotates an inclined shaft U. On the bottom of the inclined shaft is (Fig. 7) a bevel wheel V. Below the bevel wheel V are two bevel wheels W (see Fig. 7). These are united by a sleeve piece X which has a groove to receive the fork Y of a lever B¹. The said bevel wheels W and sleeve piece X are capable of a longitudinal movement upon an axle Z having a key A¹ thereon. They are moved backward and forward by the lever B¹ which is attached to a shaft C operated by a hand lever D¹.

The machine is propelled by hand as follows:—Above the platform (Figs. 1 and 2) is a traveling hand wheel E¹ which rotates a shaft F¹ having thereon an auxiliary turning wheel Y³. At the lower end of the shaft is a worm G¹ engaging with a worm wheel J¹ secured (Fig. 7) to the axle Z. The said worm G¹ is secured to the shaft in any well

known way and may be released and pushed up the shaft F¹ toward the hand wheel E¹ and out of gear with the worm wheel. Or the machine is slowly propelled (Fig. 1) by a cone pulley P² mounted on a second shaft O¹ (hereinafter described) and a belt 70 drives a cone pulley Q² mounted upon the third shaft R². A worm S² drives a worm wheel T² loosely mounted upon the shaft F¹ and capable of being secured to the shaft by a clutch U² operated by a lever V². 75

A rotary cutting tool K¹, of any desired shape, is mounted upon a spindle X¹, being operated, as follows:—The motor shaft R drives a toothed wheel L¹, coacting with an idle wheel M¹, which in turn, is in mesh with, 80 and adapted to operate, a toothed wheel N¹, mounted upon the shaft O¹. Or the shaft R may be directly connected with the second motion shaft O¹. The shaft O¹ consists of two parts, united by a friction clutch P¹, operatively connected, by a sleeve Q¹, with a lever R¹. The lever is pivotally connected with a bracket S¹ and intermediate the ends of said lever a clutch rod T¹ is secured, the same being threaded at its outer end to receive a hand wheel U¹. Mounted upon the outer end of the second motion shaft O¹ (Figs. 1 and 2) is a bevel wheel V¹ in mesh with a bevel wheel W¹ upon the top of a cutting spindle X¹. The top end of the cutting 95 spindle X¹ (Fig. 2) is supported by a screw Y¹, which does not rotate with the said spindle but is turned by a turn handle Z¹, and locked by a locking handle A².

The cutting tool K¹ may be fluted, and 100 may either deepen the groove in a street railway rail and cut off any upstanding or outstanding lip, in the one operation, or perform these operations singly. On plain headed rails it may remove the outstanding lip and 105 also reform the corner of the rail, in the one operation or separately.

The machine is adjusted (Figs. 1 and 7) laterally (when grooved rails are being treated), near the cutting tool K¹ as follows:—110 The traveling wheel B is loose on the axle Z and moves longitudinally thereon. Attached to the outer end of the axle Z is the inner end of an adjusting thread B² and on the outer end of this is a nut rotated by a hand wheel C², which nut turns within a suitable collar D² protruding from the wheel B. Outside the hand wheel C² is a locking nut E². As the hand wheel C² is rotated the wheel B moves longitudinally upon the axle Z. 115 120

When plain headed rails are being reformed, flanged or unflanged, stepped or unstepped, rollers F² are placed (Fig. 10) each side of the rail or the web, said rollers being adapted to turn in forks G². The shanks H² 125 of the forks are threaded and around the shanks are nuts J², adapted to be turned by hand wheels K² (see Fig. 2), within suitable

collars L². Locking nuts M² lock the hand wheels to the shanks and jam screws N² lock the nuts M² to the collars L². As the hand wheels K² are turned, the rollers F² are moved to or from the rails. A bracket, such as O², supporting the collars L², is attached to the platform A. If desired a pair of these rollers may be placed each side of the cutting tool.

10 Adjacent to the deformed rail, is placed (Figs. 3, 4, 5 and 6) a model rail W², of any section. The top of the model rail may be flat, or elevated, depressed or hollowed in the center, the amount of elevation or depression 15 depending upon the circumstances. Each end of this rail W² is retained within a fork above a chair X², which chair rests upon sleepers Y² and between each chair X² and the model rail W² is (Fig. 3) an adjusting 20 screw Z², the lower end of which is threaded into the chair. The screw Z² is turned by means of turning-holes A². In each end of the model rail is a hole into which passes the outer end of a threaded rod B³, provided with 25 a turning collar B³. The inner end of the rod B³ is threaded into a clamp C³ which is locked to the rail by a screw D³. By means of the adjusting screws Z² and the threaded rods B³ the said model rail W² is adjusted, as regards 30 its height and distance, from the adjoining rail.

Rail heads are ground by a grinding wheel as follows:—On the first motion shaft R is (Figs. 1 and 2) a pulley E³. This, through 35 the agency of a belt, drives a pulley F³. The pulley F³ turns a spindle G³ which is adapted to move longitudinally, said motion being effected (see also Fig. 1^a) by a fork J³ on a lever H³, the legs of which fork pass over a 40 recess in the spindle G³. The lever may engage with a toothed rack K³ and is preferably intermediately pivoted, being provided at its upper end with a handle L³. Attached to the spindle G³ and above the rail to be treated, is a grinding wheel M³, composed of any 45 desired materials and having a cutting edge of any section, said grinding wheel being adapted to be lifted from the rail by the hand wheel P which elevates the platform. To 50 the front traveling wheel B hereinbefore described is attached (Fig. 7) a toothed ring Z³ and this engages with a toothed rack A⁴ the lower flange B⁴ of which is secured to the rail flange.

55 When on railway tracks it is desired to turn the machine end for end (Figs. 1 and 8) the hand wheel N² of a turntable gear is rotated, thereby turning the bevel pinion O² and the bevel wheel P². The bevel wheel P² is secured to the top of a lifting screw Q² the top of which passes through a hole in the platform A. Beneath the platform and upon the raising screw is a collar R². The screw below the collar R² turns in a socket S²

having a bottom flange T², and embracing 65 the socket is a guide U² secured underneath the platform by a flange V².

We do not wish to be understood as limiting ourselves to the exact details of construction and arrangement described, since various slight and immaterial modifications may be made therein without departing from the spirit and the scope of our invention.

Our invention is operated as follows:—When it is desired to propel the machine 75 rapidly, either backward or forward by power (Figs. 2 and 7) the hand lever D¹ is pulled either backward or forward respectively. This moves the sleeve X (Fig. 7) upon the axle Z and thereby causes one of 80 the bevel wheels W to engage with the bevel wheel V. The said bevel wheel V is driven by the inclined shaft U which is driven (Figs. 1 and 2) by the worm wheel T. The worm wheel T is driven by the worm S positioned 85 upon the first motion shaft R. When it is desired to propel the machine moderately fast by power (Fig. 1), the hand wheel U¹ is turned, throwing the friction clutch P¹ into gear. A belt between the cone pulleys P² 90 and Q² drives (see also Fig. 2) the third motion shaft R², which drives the worm S² operated by the clutch U² upon the shaft F¹. As the shaft F¹ rotates, it turns the worm G¹ and engages (see also Fig. 7) with the worm 95 wheel J¹ secured to the axle Z. When it is desired to propel the machine by hand, (Figs. 1 and 2) the traveling hand wheel E¹ is rotated, thereby rotating the shaft F¹ and the worm wheel J¹. When it is desired to move the 100 front end of the platform laterally over grooved rails, (Figs. 1 and 7) the hand wheel C² is turned, whereby the axle Z is projected into or out of the traveling wheel B. In addition to the movement of the front end of 105 the platform over grooved rails, it is often necessary to accomplish the movement of the machine laterally over plain headed rails and when the machine is to be adjusted laterally over plain headed rails, the hand 110 wheels K² (Fig. 10) are rotated in order to move the platform transversely as regards the rail. When a defective joint, such as seen in Fig. 6, requires reforming, a model rail W² is placed adjacent to the deformed one. It is evident that the model rail W² may be placed adjacent such a rail as shown in Fig. 10, or that shown in Fig. 5, but it is 115 obvious that the deformity in the rail shown in Fig. 10 must be distant from the forks G² in order to permit of the model rail being placed adjacent to said deformity, and it is obvious that said forks G² do not necessarily necessitate the exclusion of the model rail in those instances when it is desired to clamp the machine to the rail as shown in Fig. 10. The top of the model rail is of such a formation that the defect in the deformed rail will 120 125

be as much elongated as possible. The chairs X^2 upon which it rests are placed upon sleepers Y^2 . Then adjusting screws Z^2 are turned (Fig. 3) and the said model rail is elevated (and platform A if necessary). Or the back end of the platform can be elevated by turning the hand wheel G, which forces the wheel F on to a cross-over rail placed beneath it. The platform can then be lowered on to the model wheel and rail. The hand wheel P is then turned (Figs. 1 and 2) and the model rail wheel Q descends on to the model rail W^2 and supports the platform A. The grinding wheel M^3 is then vertically adjusted to the deformed rail and the platform A is moved backward or forward by hand or by power. When grooved rails require lips in the grooves removed or the said grooves deepened, the cutting spindle X¹ may be supplied at its lower end with a suitable cutting tool K¹ for either removing the lip or deepening the groove, or both.

Having now described our invention what we claim as new and desire to secure by Letters Patent is:—

1. In a portable machine for treating rail deformities *in situ*; the combination comprising a platform; a rotatable tool arranged to project below said platform; means for optionally elevating or depressing said tool with respect to a rail treated; and means for causing the lower end of said tool to repeatedly contact with the surface of a limited portion of said rail when successively maintained at different elevations with respect to the base of said rail while successively traveling in superposed paths out of alignment with the longitudinal axis of the rail treated and respectively parallel to a surface of predetermined configuration; said means comprising a model-rail having a tread of predetermined configuration with respect to a deformity in the rail treated; means for securing said model-rail in a fixed position with respect to the rail treated; and means for supporting that portion of the platform adjacent said tool at a uniform distance from the surface of said model-rail during the movement of the platform longitudinally of the same; substantially as described.

2. In a portable machine for treating rail deformities *in situ*; the combination comprising a platform; a rotatable tool arranged to project below said platform; means for optionally elevating or depressing said tool with respect to a rail treated; and means for causing the lower end of said tool to repeatedly contact with the surface of a limited portion of said rail when successively maintained at different elevations with respect to the base of said rail while successively traveling in superposed paths out of alignment with the longitudinal axis of the rail treated and respectively parallel to a surface of pre-

determined configuration; said means comprising a model-rail having a tread of predetermined configuration with respect to a deformity in the rail treated; means for securing said model-rail in a fixed position with respect to the rail treated and a traveling wheel journaled in bearings carried by said platform, adapted to maintain that portion of the platform adjacent said tool at a uniform distance from the surface of said model-rail during the movement of the platform longitudinally of the same; substantially as described.

3. In a portable machine for treating rail deformities *in situ*; the combination comprising a platform; wheels adapted to support and propel said platform; a rotary cutting tool mounted upon a spindle; means on said spindle for vertically adjusting said cutting tool; a rotor element; a plurality of means for operatively connecting said rotor element with one of said propelling wheels and adapted to drive said wheel at differential speeds; and means for moving said platform laterally with respect to said propelling wheel; substantially as described.

4. In a portable machine for treating rail deformities *in situ*; the sub-combination comprising a propelling wheel mounted upon an axle and longitudinally movable with respect thereto; means for reciprocating said axle, comprising an adjusting screw connected with one end of said axle, a nut threaded thereon, and a collar independent of said nut and secured intermediate the said axle and said nut; a sleeve upon the opposite end of said axle; opposing bevel gears secured to each end of said sleeve; means for reciprocating said sleeve along said axle; a toothed ring concentrically connected to said wheel; and a worm wheel rigidly secured to said axle; substantially as described.

5. In a portable machine for treating rail deformities *in situ*; the sub-combination comprising a platform; a rotatable cutting tool mounted thereon; and means for adjusting said platform laterally with respect to the rail treated; said means including a plurality of oppositely disposed bearings, adapted to optionally engage with opposite sides of the rail treated, adjustable supports for said bearings, and means for locking said supports in any desired position; substantially as described.

6. In a portable machine for treating rail deformities *in situ*; the combination comprising a platform; an elevating screw positioned below said machine at the center of gravity thereof and projecting upwardly through said platform; a bevel gear-wheel mounted upon the upper end of said screw; a collar on said screw adapted to engage with the lower face of the platform; a support

provided with a threaded socket adapted to receive the lower end of said screw; a guide-sleeve secured to said platform and surrounding said support; a pinion adapted to actuate said bevel gear-wheel; and means for actuating said pinion; substantially as described.

In testimony whereof we affix our signa-

tures in the presence of two subscribing witnesses.
